UNITED STATES PATENT OFFICE.

ARTHUR A. BULL, OF DETROIT, MICHIGAN, ASSIGNOR TO GENERAL MOTORS CORPORATION, OF DETROIT, MICHIGAN, A CORPORATION OF DELAWARE.

COOLING-JACKET CONSTRUCTION FOR INTERNAL-COMBUSTION ENGINES.

Application filed August 2, 1920. Serial No. 400,756.

To all whom it may concern:

Be it known that I, ARTHUR A. BULL, a subject of the King of Great Britain, and a resident of Detroit, county of Wayne, and

5 State of Michigan, have invented certain new and useful Improvements in Cooling-Jacket Constructions for Internal-Combustion Engines, of which the following is a full, clear, concise, and exact description,

10 such as will enable others skilled in the art to which the invention relates to make and use the same, reference being made therein to the accompanying drawings, which form a part of this specification.

15 My invention relates to internal combustion engines; and particularly to the construction and arrangement of the cooling liquid space or water jacket thereof whereby the cylinders and combustion chambers, 20 and the valves and other parts of the engine, are cooled and maintained at a proper temperature for effective operation.

The principal object of my invention is to provide certain new and improved features 25 of construction and arrangement in and relating to the cooling liquid jacket of an internal combustion engine; with the end in view of equalizing the flow of cooling liquid to the several parts of the engine to be 30 cooled, so that the various portions in question will be properly and sufficiently cooled when the engine is in use.

A further object of my invention is to provide an improved cooling jacket construction for internal combustion engines in 35 which the cooling liquid is caused to flow adjacent the valves of the engine immediately as it enters the cooling liquid space or cooling jacket, and in which means are 40 provided for regulating the flow of cooling liquid in the vicinity of the valves in such a manner as to secure substantially equal cooling effect as regards each of the valves with which the engine is provided.

45 A further object of my invention is to provide an improved cooling liquid jacket construction for multiple cylinder internal combustion engines wherein the flow of cooling liquid is distributed throughout the 50 cylinder block wherein the several cylinders are contained, and throughout the head which closes the upper end of said block in such a manner as to secure proper cooling effect as regards each of the several parts 55 to be cooled; the construction and arrange-

ment of the cooling means or jacket structure in question being such as to secure a supply of cooling liquid directly to the vicinity of the valves of the engine in the first instance, and thereafter to cause the cooling 60 liquid to circulate through the cylinder block, and from thence into the head of the engine.

With the above and other objects of invention in view, my invention consists in the 65 improved cooling liquid jacket construction and arrangement for multiple cylinder internal-combustion engines illustrated in the accompanying drawings and hereinafter described and claimed; and in such variations 70 and modifications thereof as will be obvious to those skilled in the art to which my invention relates so long as such modifications come within the scope of the concluding 75 claims wherein the distinguishing features of my invention are particularly pointed out.

Referring now to the drawings wherein the preferred embodiment of my invention is illustrated:

Figure 1 is a view showing a multiple cylinder internal combustion engine provided with a cooling system made in accordance with my invention the view being for the most part in plan but certain portions of 85 the engine being broken away to better show features of construction otherwise hidden.

Figure 2 is a view showing a section upon a vertical plane indicated by the line 2, 2, 90 Figure 1.

Figure 3 is a view showing a section upon a vertical transverse plane indicated by the lines 3, 3, Figures 1 and 2 the impeller of the pump however being omitted.

Figure 4 is a view showing a section upon a vertical transverse plane indicated by the line 4, 4, Figures 1 and 2.

Referring now to the drawings, the reference numeral 5 designates a cylinder block 100 having a plurality of cylinders formed therein as indicated by the reference numeral 6 and which cylinder block is provided with an internal cooling liquid space formed by a jacket surrounding the said 105 cylinders, the jacket space within the block being ordinarily common to all the cylinders thereof as is usual in internal combustion engines of the type to which my invention relates.

100

110

Located within the space enclosed by the cooling jacket of the cylinder block is a partition 7, which partition extends longitudinally of the block and is disposed adjacent the upper end thereof; the said partition serving to divide a portion of the cooling liquid jacket space of the cylinder block designated by the reference numeral 8 from the main portion 9 of said jacket space, the portion 8 thus isolated or divided off providing in effect a passage extending longitudinally of the cylinder block and located adjacent the head end thereof, as best shown in Figures 1 and 4. The cooling liquid is supplied to this space or passage through an inlet port 10 which is in communication with the outlet of a suitable cooling liquid circulating pump; the casing of the pump being designated by the reference numeral 11 and which pump is illustrated as of the centrifugal type, the rotary impeller thereof being designated by the reference numeral 12 in Figure 1.

The longitudinally extending partition 7 is shown as provided with a plurality of bosses 13 formed integral therewith as the cylinder block is cast and which bosses provide bearings for the stems of the several supply and exhaust valves with which the engine is equipped, the seats of said valves being designated by the reference numeral 14 in Figure 4 and which valves are of the ordinary poppet variety, although they are not shown in the drawing; the said valves being obviously arranged along the partition in question, and properly spaced relative to the several cylinders so as to secure a proper supply of combustible mixture to and a proper flow of burned gases from the several cylinders.

The partition 7 is shown as provided with a plurality of holes spaced along its length and indicated by the reference numerals 15, and through which holes the cooling liquid which is supplied to the isolated or divided off portion of the water jacket space 8 as aforesaid may escape from the said space at several points along the length of the partition; the cooling liquid as it flows through the holes entering into the main cooling liquid space 9 enclosed by the jacket of the engine, as will be appreciated. The end of the partition 7 remote from the inlet port 10 through which the cooling liquid is supplied to the passage 8 terminates short of the adjacent jacket wall, as shown at 16 in Figure 1, so that such cooling liquid as may not pass through the several holes 15 in the partition will nevertheless flow into the main jacket space of the cylinder block at a point remote from the point at which the cooling liquid is supplied to the said block and isolated cooling liquid passage 8.

It will therefore be appreciated that the cooling liquid supplied to the passage 8

through the port 10 flows out therefrom through the holes 15 and, inasmuch as the area of outflow provided by said holes is limited adjacent the port 10, it follows that a continually diminishing volume of cooling liquid will flow along the passage 8 and toward the rear end thereof; as the total area provided by all the openings 15 is commonly less than the area of the inlet port 10 leading into said passage. This scheme of providing for the escape of the cooling liquid from the partitioned off portion 8 of the jacket space at various points provides a cooling system in which a supply of comparatively cool liquid is secured for the valves which are located remote from the inlet end 10 of the said passage, and secures substantially equal cooling effect as regards each of the valves.

The open upper end of the cylinder block is closed by a cylinder head 17 which is hollow to thereby provide an internal cooling liquid or jacket space for the head, and the interior of the jacket space of the head is placed in communication with the jacket space of the cylinder block; so that the cooling liquid which is supplied to the block rises into the hollow head and escapes therefrom through a manifold or passage 18 of gradually increasing area, as best shown in Figure 2, from which passage the same flows through a suitable conduit 19 to the upper end of the radiator 20, downward through said radiator, and from the lower end thereof through a conduit 21 to the pump 11.

Preferably the interior of the cylinder head 17 is placed in communication with both the portions of the jacket space which are separated by the partition 7, that is with both the isolated portion or passage 8 and with the main portion 9 of the said jacket space; the communication between the portion 8 and the interior of the head being established through a plurality of passages 22 spaced along the cylinder block from end to end thereof and through which a graduated outflow of cooling liquid from the said passage upward, and into the interior of the head provided for; while the main portion 9 of the jacket space is placed in communication with the interior of the head through similar passages 23 likewise spaced along the cylinder block and which provide for a flow of cooling liquid from the said jacket space into the interior of the head at several points along the length of the block.

The areas of the several passages 22, 23, as well also as of the passages 15 provided in the partition 7, are so proportioned as to secure an equalization of the flow of cooling liquid throughout the entire system whereby a proper temperature will be maintained at all the parts of the engine to be cooled; the holes 15 and 22 being of re- 130

stricted area so as to prevent the cooling liquid supplied through the port 10 from leaving the passage 8 at the end of the block adjacent the said port, and so as to cause a flow of the inflowing cooling liquid toward the remote end of the cylinder block, as hereinbefore explained. The cooling liquid escaping through the holes 22 passes directly into the interior of the head, while the cooling liquid escaping through the openings 15 passes into the main portion 9 of the jacket space and from thence into the interior of the head through the passages 23, as will be appreciated, so that all the cooling liquid supplied through the port 10 eventually reaches the interior of the head and escapes therefrom through the outlet passage 18 to the radiator.

The cooling liquid inlet conduit 21 is connected with an elbow 24 located at one end of the cylinder block; and the cylinder block at the end in question is provided with an internal chamber 25 into which the cooling liquid is discharged, and which chamber is separated from the jacket space of the block by a suitable wall as shown at 26 in Figure 1. This chamber is provided with an annular outlet opening 27 which lies substantially in the plane of the end of the block and which opening leads into the interior of the pump casing 11, thus supplying cooling liquid thereto; the said pump casing being detachably secured to the end wall of the said chamber and of the cylinder block as by means of a series of bolts 28. The cooling liquid acted upon by the impeller of the pump is discharged therefrom through an outlet passage 29 which registers with the port 10 above referred to; and the inlet end of the passage 8 adjacent the outlet passage 29 and port 10 is divided off from the chamber 25 into which the inflowing water is discharged through the elbow 24 by suitable side and end walls 30, the outlet passage 31 thus extending through the inlet chamber 25 of the pump, as best shown in Figures 1 and 3 of the drawings.

The impeller 12 is carried by a combined fan and propeller shaft 32 which is rotatable in a bearing carried by the pump casing 11, as shown, and the inner end of which shaft is preferably steadied by and supported in the end of a bearing provided in a boss 33 which projects from the inner wall 26 of the cooling liquid receiving chamber 25; and it will be appreciated that the pump features of my invention here described provide a pump the casing of which is open along one side, and which may therefore be cast without the use of a core; and that the entire pump mechanism may be easily assembled with the engine and is firmly supported therefrom in an easily accessible position.

Having thus described and explained my

invention, I claim and desire to secure by Letters Patent:

1. In an internal combustion engine, a cylinder having a cooling liquid space; a partition separate from and disposed substantially parallel with the axis of said cylinder, and spaced apart from the wall thereof and located within and serving to divide a portion of said cooling liquid space from the main part thereof; means for supplying a cooling liquid to the part of the cooling liquid space thus isolated; and a plurality of holes provided in and spaced along said partition and through which the portion of the cooling liquid space isolated as aforesaid is placed in communication with the main part thereof.

2. In an internal combustion engine, a cylinder having a cooling liquid space; a partition located within and serving to divide a portion of said cooling liquid space from the main part thereof; means for supplying a cooling liquid to the part of the cooling liquid space thus isolated; a plurality of valves arranged along said partition; a plurality of holes provided in and spaced along said partition and through which the portion of the cooling liquid space isolated as aforesaid is placed in communication with the main part thereof; a hollow head for closing the upper end of said cylinder; and means whereby the interior of said head is placed in communication with the cooling liquid space aforesaid.

3. In an internal combustion engine, a cylinder block having a plurality of cylinders, and a cooling liquid jacket whereby said cylinders are cooled; a partition separate from and disposed substantially parallel with the axes of said cylinders and located within the space enclosed by said jacket, and extending longitudinally of said block and serving to divide a portion of said jacket space from the main part thereof; means for supplying a cooling liquid to the part of the jacket space thus isolated; and a plurality of holes provided in and spaced along said partition and through which the portion of the jacket space isolated as aforesaid is placed in communication with the main part thereof.

4. In an internal combustion engine, a cylinder block having a plurality of cylinders, and a cooling liquid jacket space common to all of said cylinders; a partition located within the space enclosed by said jacket and extending longitudinally of said block, and serving to divide a portion of said jacket space from the main part thereof; means for supplying a cooling liquid to the part of the jacket space thus isolated; a plurality of valves arranged along said partition; and a plurality of holes provided in and spaced along said partition, and through which the portion of the jacket space isolated as aforesaid is placed in communication with the main part thereof.

41
said is placed in communication with the main part thereof.

5. In an internal combustion engine, a cylinder block having a plurality of cylinders, 5 and a cooling liquid jacket space common to all said cylinders; a partition located adjacent the upper or head end of said block and extending longitudinally thereof, and serving to divide a portion of said jacket space 10 from the main part thereof; means for supplying a cooling liquid to the part of the jacket space thus isolated; a plurality of valve stem guides arranged along said partition; a plurality of holes provided in and 15 spaced along said partition, and through which the portion of the jacket space isolated as aforesaid is placed in communication with the main part thereof; a hollow head for closing the upper end of said cylinder 20 block; and means whereby the interior of said head is placed in communication with the jacket space within said cylinder block.

6. In an internal combustion engine, a cylinder block having a plurality of cylinders, 25 and a cooling liquid jacket space common to all said cylinders; a partition located adjacent the upper or head end of said block and extending longitudinally thereof, and serving to divide a portion of said jacket 30 space from the main part thereof; means for supplying a cooling liquid to the part of the jacket space thus isolated; a plurality of valve guides formed integrally with said partition and arranged along the same; a 35 plurality of holes provided in and spaced along said partition, and through which the portion of the jacket space isolated as aforesaid is placed in communication with the main part thereof; a hollow head for closing the upper end of said cylinder block; a plurality of cooling liquid passages spaced 40 along said block and through which the isolated portion of said cooling liquid space is placed in communication with the interior 45 of said head; and a plurality of passages spaced along said cylinder block and through which the main portion of said cooling liquid jacket space is placed in communication with the interior of said head.

50 7. In an internal combustion engine, a cylinder block having a plurality of cylinders, and a cooling liquid jacket space common to all said cylinders; a partition located adjacent the upper or head end of said 55 block and extending longitudinally thereof, and serving to divide a portion of said jacket space from the main part thereof; a pump secured to one end of said cylinder block; a discharge conduit leading from 60 said pump and discharging into the portion of the jacket space isolated by said partition; and a plurality of holes provided in and spaced along said partition, and through which the jacket space isolated as aforesaid is placed in communication with the main part thereof.

aforesaid is placed in communication with the main part thereof.

8. In an internal combustion engine, a cylinder block having a plurality of cylinders, and a cooling liquid jacket space common to all said cylinders; a partition located adjacent the upper or head end of said block and extending longitudinally thereof, and serving to divide a portion of said jacket space from the main part thereof; a pump secured to one end of said cylinder block; a discharge conduit leading from said pump and discharging into the portion of the jacket space isolated by said partition at one end thereof; a plurality of valves arranged along said partition; a plurality of holes provided in and spaced along said partition, and through which the jacket space isolated as aforesaid is placed in communication with the main part thereof; a hollow head for closing the upper end of said cylinder block; and a plurality of passages spaced along said cylinder block and through which both the isolated and the main portions of said cooling liquid jacket are placed in communication with the interior of said head.

9. In an internal combustion engine, a cylinder having a cooling liquid jacket space; a cooling liquid receiving chamber separated from said jacket space by a dividing wall, and which chamber has an outer wall provided with an opening; a pump casing secured to said outer wall over the opening aforesaid; means for establishing a flow of cooling liquid from said chamber into said pump casing; and an outlet conduit leading from said pump casing and discharging into the cooling liquid jacket space of the engine.

10. In an internal combustion engine, a cylinder having a cooling liquid jacket space; an internal cooling liquid receiving chamber separated from said jacket space by a dividing wall, and which chamber has an outer wall provided with an opening; a pump casing secured to said outer wall over the opening aforesaid; a rotating impeller located within said pump casing for establishing the flow of cooling liquid from said chamber into said casing; and an outlet conduit leading from said pump casing and discharging into the cooling liquid jacket space of the engine.

11. In an internal combustion engine, a cylinder block having a cooling liquid jacket space; a cooling liquid receiving chamber located at one end of said block and separated from said jacket space by a dividing wall, and which chamber has an outer wall provided with an opening; a pump casing secured to said outer wall over the opening aforesaid; a rotating impeller located within said pump casing for establishing

the flow of cooling liquid from said chamber into said casing; and an outlet conduit leading from said pump casing through said liquid receiving chamber, and which 5 conduit discharges into the cooling jacket space of the engine.

12. In an internal combustion engine, a cylinder block having a plurality of cylinders, and a cooling liquid jacket space; 10 an internal cooling liquid receiving chamber located at one end of said block and separated from said jacket space by a dividing wall, and which chamber has an outer wall provided with an opening; a pump 15 casing secured to said outer wall over the opening therein; a rotating impeller located within said pump casing for establishing a flow of cooling liquid from said chamber into said casing; and an outlet conduit leading 20 from said pump casing through said

liquid receiving chamber, and discharging into the cooling liquid jacket space of the engine.

13. In an internal combustion engine, a cylinder having a cooling liquid jacket 25 space; a cooling liquid receiving chamber separated from said jacket space by a dividing wall, and which chamber has an outer wall provided with an opening; a pump casing secured to said outer wall over said 30 opening; a rotating impeller within said pump casing for establishing a flow of cooling liquid from said chamber into said casing; and an outlet conduit leading from 35 said pump casing through said liquid receiving chamber, and discharging into the cooling liquid jacket space of the engine.

In testimony whereof I affix my signature.

ARTHUR A. BULL.
